COMBINED CAMERA AND FLASHGUN

Samuel Kitrosser, 23 Oakland St., Lexington, Mass.
02173, and Frederick W. Macone, Cross St., Carlisle,
Mass.

Filed Mar. 25, 1965, Ser. No. 84,431

Term of patent 14 years

(Cl. D61—1)

FIG. 1.

FIG. 2.

FIG. 1 is a perspective view of a combined camera and flashgun showing our new design, the flashgun being detached; and

FIG. 2 is a rear perspective view thereof, on a reduced scale, with the flashgun in operative position atop the camera.

The bottom of the camera, not shown, is substantially plain and unornamented. The bottom of the flashgun, except for the provision of a conventional six-prong plug for attaching to the receptacle in the top of the camera, is substantially plain and unornamented. The essential features of our design are shown in full lines.

We claim:

The ornamental design for a combined camera and flashgun, shown in full lines.
